UNITED STATES PATENT OFFICE

ARTHUR C. PRINCE, OF CHICAGO, ILLINOIS

BANK

Application filed February 26, 1926. Serial No. 90,740.

This invention relates to a bank, and particularly to a pocket bank and to the locking mechanism for such bank. It has for one object to provide a removable and locking lid for a bank. Another object is to provide in such a lid a locking mechanism with a minimum of moving parts. Another object is to provide in such a lid a locking mechanism which will lock the bank equally 10 at widely separated points. Other objects will appear from time to time throughout the specification and claims.

My invention is illustrated more or less diagrammatically in the accompanying 15 drawings, wherein:

Figure 1 is a view in perspective of the bank;

Figure 2 is a plan view of the lid;

Figure 3 is a horizontal cross section on 20 line 3-3 of Figure 1, drawn on an enlarged scale;

Figure 4 is a section taken on line 4-4 of Figure 3;

Figure 5 is a side elevation of the lid on 25 the same scale used in Figures 3 and 4;

Figure 6 is a section through the lid taken on line 6-6 of Figure 5;

Figure 7 is a view of the key;

Figure 8 is a section taken on line 8-8 30 of Figure 3 showing the key in position;

Figure 9 is a perspective view of one of the locking lugs.

Like parts are indicated by like characters throughout.

A is the shell of a bank. B is the lid. The lid B is provided with an inwardly or downwardly projecting skirt B¹ and a laterally extending flange B². The lid is provided with a more or less conical inwardly bent portion B³ which is formed integral, preferably, with the remainder of the lid but need not be so. Pivotaly mounted in the portion B³ of the lid is a locking cam C. This cam is provided with a pair of cam faces C¹ C² each of which terminates in a bent nose C². C³ C⁴ are stop portions mounted on the cam C. In the form here shown the cam C has inwardly bent from it a ferrule or engaging portion C⁴ which engages the inwardly bent portion B³ of the lid so that the

cam may be rotated about the center of the lid, which is perforated to receive it.

D D are locking lugs. Each of them is provided with a narrowed portion D¹, which portion is engaged by the inwardly bent ears D² formed in the skirt B¹ of the lid B. By means of these ears, the lugs are held in position but are permitted to tilt with relation to the lid. The lid is provided with a pair of slots D³ D⁴ which are preferably 55 located diametrically opposite each other. D⁴ is the locking nose of the lug D. It is mounted so as to project through the slot D³, into the groove D⁵.

E is a filler member and E¹ is a cover which 65 is mounted at the outer end of the lid B and serves to give a finished appearance and to carry a label or other device. It is provided with a perforation or key hole E².

While I have shown an operative device, 70 still it will be obvious that many changes might be made in size, shape and arrangement of parts without departing materially from the spirit of my invention; and I wish therefore that my invention be taken as in a sense 75 diagrammatic.

The use and operation of my invention are as follows:

As shown in Figure 3 the lid is in position and is locked. In order to unlock it, the key 80 is used and is moved so as to rotate the cam plate C, and the nose C² moves from a position in the rear of the locking nose D⁴ and in so moving slides along the inner surface of the locking lug D and tilts it and finally 85 comes to rest with the nose C² at the inner end of the lug. This is the relation shown in Figure 6 and in that position the locking lugs have been tilted so as to withdraw the locking nose back within the skirt portion 90 of the lid. Excess movement in this direction is prevented by stops C³ which contact the lugs D as shown. When the parts have been moved into this position, the lid may be removed. In order to relock the lid, it must be put in position and the key turned in the reverse direction, moving the locking nose C² so as to force the part D⁴ again outward 95 through the slot D³ and into locking position shown in Figure 3.

I claim:

1. In combination with a receptacle having an opening, a removable cover therefor, a plurality of locking lugs and an unattached movable controlling member adapted to be moved in one direction to move said lugs into the locking position and adapted to be moved in the opposite direction to withdraw them from locking position, and stops on such member to limit its movement in either direction, said controlling member having frictional contact with said locking lugs.
2. In combination with a receptacle having an opening, a removable closure therefor and locking means for such closure, including a curved member mounted for rotation within the closure and provided with a locking lug adapted, when such curved member is in one position of rotation, to be withdrawn from locking position, and when such curved member is in another position of rotation to extend into locking position, to lock the same in position in the receptacle, and a curved locking cam member mounted for rotation on such closure and provided with a cam portion adapted to contact such curved locking member, and to move it into and out of the locking position.
3. In combination with a receptacle having an opening, a removable closure therefor and means for locking such closure in position, such closure formed with an inwardly extending skirt portion, such locking means being mounted within such portion, and including a tilttable locking member having a locking lug in combination with a pair of inwardly bent lugs formed integrally with such skirt portion and engaging and supporting such locking member for movement.
4. In combination with a receptacle having an opening, a removable closure therefor and means for locking such closure in position, such closure formed with an inwardly extending skirt portion, such locking means being mounted within such portion, and including a tilttable locking member having a locking lug in combination with a pair of inwardly bent lugs, formed integrally with such skirt portion and engaging and supporting such locking member for movement, in combination with a cam member mounted for rotation within such skirt portion and provided with a cam face adapted to engage such locking member and in one position to withdraw it within the skirt portion and in another position to force it outward beyond the skirt portion to lock the closure in position within the receptacle.

Signed at Chicago, county of Cook, and
State of Illinois, this 20th day of February,
1926.

ARTHUR C. PRINCE.
